STUDY CARRELL

Robert M. Courtwright, Tacoma, Wash., assignor to
Educators Manufacturing Company, Tacoma, Wash.

Filed May 15, 1963, Ser. No. 74,894

Term of patent 14 years

(Cl. D33—11)

Fig. 1

Fig. 2

Fig. 3

FIGURE 1 is an isometric view of a study carrell embodying my new design;

FIGURE 2 is a top plan view on a reduced scale; and

FIGURE 3 is a side elevational view thereof.

The four sides of the study carrell are all identical.

I claim:

The ornamental design for a study carrell, as shown and described.
